Primary Examiner — Jack Reickel
Assistant Examiner — Salamah Jordan(57) **CLAIM**

The ornamental design for a weight vest with attachments, as shown and described.

DESCRIPTION

FIG. 1 is a top front perspective view of a weight vest with attachments showing my new design;

FIG. 2 is a bottom rear perspective view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front elevational view thereof;

FIG. 8 is a back elevational view thereof;

FIG. 9 is a top front perspective view of the weight vest with attachments in an alternative position; and,

FIG. 10 is a bottom rear perspective view thereof.

The broken line showing attachments in FIGS. 9 and 10 is included for the purpose of illustrating environmental structure and forms no part of the claimed design.

1 Claim, 10 Drawing Sheets(56)
